US0D1088237S

(12) **United States Design Patent** (10) **Patent No.:** **US D1,088,237 S**
(45) **Date of Patent:** **** Aug. 12, 2025**

(54) **ORAL IRRIGATION DEVICE**

(71) Applicant: **Swiftsure Innovations Inc.**, Pasadena (CA)

(72) Inventors: **Deanne McCarthy**, Pasadena (CA); **Christopher Gillespie**, Toronto (CA); **Kathryn Atwell**, Halifax (CA); **Joel Ironstone**, Toronto (CA); **Matthew Asselin**, Toronto (CA); **Angie Hughes**, Corner Brook (CA); **Rory Tatchell**, Corner Brook (CA)

(73) Assignee: **Swiftsure Innovations Inc.** (CA)

(**) Term: **15 Years**

(21) Appl. No.: **29/833,875**

(22) Filed: **Apr. 7, 2022**

Related U.S. Application Data

(63) Continuation-in-part of application No. 29/824,148, filed on Jan. 21, 2022.

(57) **CLAIM**

The ornamental design for an oral irrigation device as shown and described.

DESCRIPTION

FIG. 1 is a front-left perspective view of an oral irrigation device showing the new design;

FIG. 2 is a front-right perspective view of the oral irrigation device of FIG. 1;

FIG. 3 is a front elevational view of the oral irrigation device of FIG. 1;

FIG. 4 is a rear elevational view of the oral irrigation device of FIG. 1;

FIG. 5 is a top plan view of the oral irrigation device of FIG. 1;

FIG. 6 is a bottom plan view of the oral irrigation device of FIG. 1;

FIG. 7 is a left side elevational view of the oral irrigation device of FIG. 1; and,

FIG. 8 is a right side elevational view of the oral irrigation device of FIG. 1.

The broken lines in the figures illustrate portions of the oral irrigation device that form no part of the claimed design.

1 Claim, 8 Drawing Sheets
